METHOD OF STABILIZING FATS AND OILS
AND COMPOSITIONS OBTAINED THEREBY

Noel H. Kuhrt, Rochester, N. Y., assignor to Eastman Kodak Company, Rochester, N. Y., a corporation of New Jersey

No Drawing. Application October 26, 1951,
Serial No. 253,469

12 Claims. (Cl. 99—163)

1

This invention relates to methods of stabilizing fats and oils and to the stabilized compositions obtained thereby.

Fatty materials such as fatty acids, animal fats and vegetable oils are normally subject to deleterious effects of oxidation as evidenced by the development of rancidity, flavor reversion, and the like. It has been the practice to refine and deodorize such fatty materials and to stabilize them with fat-soluble antioxidants such as citric acid, propyl gallate, butylated hydroxy anisole and similar well-known antioxidants for fatty materials, the antioxidants being employed alone or in various synergistic combinations.

It is desirable, however, to stabilize the fats and oils to a greater degree than heretofore in order to prolong the shelf stability of such materials and lessen the necessity for refrigeration.

It is accordingly an object of this invention to provide a new method of treating fatty materials normally subject to oxidation to obtain fatty compositions having greatly enhanced stability against the deleterious effect of oxidation.

It is also an object of this invention to provide a new method of preparing improved fatty compositions without the inclusion of said composition of materials not normally used in food-stuffs.

It is a further object of this invention to provide fatty triglyceride compositions having stabilities greater than were obtainable heretofore by conventional practices.

Another object of the invention is to provide a simple and commercially feasible method of preparing edible fats and oils of improved stability against oxidation.

Another object of the invention is to provide a method of preparing fatty compositions not subject to objectionable peroxide formation under normal storage and handling conditions and yet consisting predominantly of fatty materials normally subject to oxidation.

Another object of the invention is to treat fats and oils in such way that the subsequent addition of conventional fat-soluble antioxidants gives greatly improved stability as compared to conventional stabilization techniques.

Another object of the invention is to provide improved methods of making animal fats and vegetable oils stable against oxidation.

Another object of the invention is to provide lard and vegetable oils of greater inherent stability against objectionable peroxide formation than that of conventional lard and vegetable oils.

Another object of the invention is to advance

5

10

15

the technology of fats and oils and make it possible to supply consumers with improved fats and oils, and particularly edible fats and oils commonly used in the home.

Other objects will be apparent from the description and claims which follow.

These and other objects are attained by means of this invention which comprises washing fatty materials normally subject to oxidation, such as fats, including fatty acids, and fatty oils, with solutions of glycine and phosphoric acid while the fatty material is in liquid form, and separating the washing solution from the fatty material following the washing, the resulting washed fatty material having enhanced stability against oxidation. If desired, a conventional fat-soluble antioxidant or combination of antioxidants can thereafter be added to the washed fatty material and the stability thereby further increased beyond that obtainable with such antioxidant alone.

The fatty compositions prepared in accordance with this invention consist predominantly of fatty material normally subject to oxidation. Such fatty materials include both solid and liquid fats and fatty oils, whether natural or synthetic, and particularly animal and vegetable fats and fatty oils and fat-forming fatty acids. The invention will find wide use in the preparation of stable fatty triglyceride compositions such as lard, cottonseed oil, soybean oil, peanut oil, marine oils, coconut oil, corn oil and the like as well as stable fatty acid compositions such as oleic acid, linoleic acid and similar fatty acids subject to oxidation.

The washing of such fatty materials is effected with the fatty materials in liquid form for optimum results and is carried out on normally solid fats in the molten state but not substantially above 90° C. and preferably below 95° C. for either the solid fats or the fatty oils. At temperatures substantially above 90° C. as for example at temperatures above 96° C. or 100° C., the effectiveness of the washing process is greatly reduced. Desirably, the washing is effected at a temperature not substantially lower than 50° C. for best results without extended washing time, temperatures of as low as 40° C. being considered below the desired minimum temperature for practical operations in most cases. The washing time will, of course, depend upon the temperature employed, and washing times of from 3 to 4 minutes to about thirty minutes will ordinarily be suitable in the preferred temperature range from about 50° C. to about 90° C. Longer washing times are

2

permissible and do not deleteriously affect the results but, of course, the longer times are usually less economical for commercial practice even though washing times of as much as 4 hours or more are considered to be within the scope of the invention.

The fatty material is washed with glycine and phosphoric acid in solution, the washing solution preferably including both the glycine and phosphoric acid in a single solution although separate solutions can be employed in some cases. The solvent employed must be a polar solvent which is immiscible with and does not dissolve the fatty material but which does dissolve the glycine and phosphoric acid. The solvent should not form an emulsion during the washing whereby separation following washing is complicated by emulsion formation. Water, glycerine and aqueous alcohols, such as aqueous methanol, aqueous ethanol, aqueous isopropanol and the like, have been found to be practical solvents for use in practicing this invention with water being preferred from the economic standpoint.

The glycine and phosphoric acid are desirably employed in substantially equal proportions and preferably with the phosphoric acid amounting to not more than twice the weight of glycine, although higher proportions of glycine are not undesirable but usually not necessary. The concentration of glycine and phosphoric acid in the washing solution can be varied as desired but concentrations of about 0.01% to 0.5% by weight of each of such materials are adequate, and higher concentrations are economically undesirable unless the washing solution is reused. The glycine and phosphoric acid are preferably added in the form of the free acids, but materials furnishing glycine or phosphoric acid under the conditions described produce similar results and are within the scope of the invention. Thus, the glycine can be furnished by a salt of glycine, such as the sodium salt, or by a crude amino acid composition containing glycine and obtained by hydrolysis of proteinaceous matter such as soybean meal or the like; and the phosphoric acid can be added in the form of the sodium salt or similar material furnishing phosphoric acid. The washing process can be carried out in accordance with any of the well-known washing procedures for fatty oils with suitable measures being taken for agitation or otherwise causing turbulence to ensure maximum contact between the fatty material and the washing solution.

Following the washing, the fatty material can be readily separated from the washing solution by settling and phase separation, sharp phase separations being readily obtained. If desired, however, centrifugation or other well-known separation processes can be employed. Substantially all of the glycine and phosphoric acid remains in the washing solution following such washing, and the washed fatty compositions can thereafter be heated to temperatures considerably above 90° C. without deleterious effects.

One of the most significant aspects of this invention is the great improvement in stability attained with conventional fat-soluble antioxidants when employed in compositions washed in accordance with this invention as compared to the stability attained with the same antioxidants in conventional compositions. This marked improvement is clearly shown in the data set out in Table 1 illustrating the invention. It should be understood, however, that similarly improved results are obtained with any of the well-known

fat antioxidants or combinations thereof including such materials as the quinones and hydroquinones, organic carboxylic acids such as citric acid, ascorbic acid, tartaric acid, amino acids and the like, as well as esters and salts thereof, phenolic antioxidants such as the alkylated hydroxy anisoles and the like, gallates, tocopherols and other similar well-known antioxidants for fatty material.

As shown in Table 1, water or glycerine washing alone does not enhance the stability of the fatty composition nor does the use of glycine or phosphoric acid alone greatly improve the stability beyond the conventional stability obtained by simple addition of usual antioxidants to unwashed fatty materials. The application of the invention in stabilizing vegetable oils is shown in Table 1 wherein refined and deodorized cottonseed oil was treated. The washing was effected by agitating the cottonseed oil and the washing solution in a reaction vessel equipped with heating means for a period of about 30 minutes. The washing solution was then separated out by phase separation and decantation. The stability was determined by the standard active oxygen method (AOM) wherein the sample is heated at 96° C. with air bubbling through the sample and the peroxide content in millimols per kilogram of fat is determined periodically. A peroxide value (P. V.) of 20 is considered the maximum permissible limit and the stability is expressed in terms of the number of hours to reach a peroxide value of 20 under the accelerated test conditions. It should be noted that a stability of 20 hours under the accelerated test conditions is equivalent to months of ordinary shelf storage.

Table 1

Washing treatment	Wash-ing temp., ° C.	Antioxidant added after washing	Hrs. to P. V. 20 (AOM)
1. None.....			2
2. None.....		0.02% propyl gallate	8
3. None.....		0.02% citric acid	7
4. Glycerine.....	65		2
5. Glycerine.....	90		2
6. Water.....	65		2
7. Water.....	70	0.02% propyl gallate +0.02% glycine	14
8. Water+0.1% glycine.....	65		2
9. Glycerine+0.1% glycine.....	65		4½
10. Glycerine+0.5% H ₃ PO ₄	90		7½
11. Water+0.5% H ₃ PO ₄	70		5
12. Two washes with water+0.1% glycine +0.1% H ₃ PO ₄	50		22
13. One wash with water +0.1% glycine+ 0.1% H ₃ PO ₄ followed by a water wash.....	50		21
14. One wash with glycine+0.1% glycine +0.1% H ₃ PO ₄	90	0.02% propyl gallate	58

As can be seen from Table 1, conventional cottonseed oil compositions stabilized in accordance with usual practice with citric acid (test 3) or propyl gallate (test 2) have stabilities of 7 and 8 hours respectively. Compositions 12 and 13 washed in accordance with this invention and containing no added antioxidant have stabilities improved nearly 300% over such conventional compositions, and composition 14 prepared in accordance with this invention and stabilized with the same amount of the same antioxidant as composition 2 has a stability more than 700% higher than composition 2.

Similarly improved results are attained with

the normally solid fats such as lard as shown in Table 2. Prime steam rendered lard was washed twice with equal volumes of water containing 0.1% by weight of glycine and 0.1% by weight of phosphoric acid at 60° C., the washing solution separated and the stability of the washed lard evaluated by the active oxygen method.

Composition	Hrs. to P. V. 20
Lard (control)	7
Washed lard	25

A batch of commercial bleached oleic acid was similarly washed twice with water containing 0.1% glycine and 0.1% phosphoric acid at 60° C. The stability of the resulting washed oleic acid was 350% of the stability of the unwashed control sample.

This invention thus provides a simple but effective method of preparing fatty compositions consisting predominantly of fats or fatty oils, having greatly enhanced stability against objectionable peroxide formation.

The invention has been described in considerable detail with reference to certain preferred embodiments thereof but it will be understood that other fats and fatty oils can be similarly treated in accordance with the invention and that variations and modifications can be effected within the spirit and scope of the invention as described hereinabove and as defined in the appended claims.

I claim:

1. The method of making a stable fatty composition which comprises washing a composition consisting predominantly of fatty material normally subject to oxidation, in liquid form, with glycine and phosphoric acid in solution in a polar solvent which is immiscible with said fatty material, and separating said solution from said composition following said washing.

2. The method of making a stable fatty triglyceride composition which comprises washing a fatty triglyceride, in liquid form, at a temperature below 95° C. with a solution of glycine and phosphoric acid in a fat-immiscible polar solvent, and separating said solution from said fatty triglyceride composition following said washing.

3. The method of making a stable fatty triglyceride composition which comprises washing a fatty triglyceride, in liquid form, at a temperature of substantially 50°-90° C. with a solution of glycine and phosphoric acid in a fat-immiscible polar solvent selected from the group consisting of water, aqueous alcohol and glycerine, and separating said solution from said fatty triglyceride following said washing.

4. The method of making a fatty composition of improved stability which comprises washing a fatty composition consisting predominantly of fatty material normally subject to oxidation, in liquid form and at a temperature of substantially 50°-90° C., with a solution of glycine and phosphoric acid in a fat-immiscible polar solvent selected from the group consisting of water, aqueous alcohol and glycerine, separating said solution from said fatty composition following said washing, and adding an antioxidant for fatty material to the resulting washed fatty composition.

5. The method of making a stable triglyceride oil which comprises washing a normally liquid triglyceride oil with a solution of glycine and

phosphoric acid in a fat-immiscible polar solvent, said washing being effected at a temperature not substantially lower than 50° C. and not substantially higher than 90° C., and thereafter separating said solution from said triglyceride oil.

6. The method of making a stable triglyceride fat which comprises washing a triglyceride fat having a melting point of less than 90° C., in liquid form, with a solution of glycine and phosphoric acid in a fat-immiscible polar solvent, said washing being effected at a temperature not substantially lower than 50° C. and not substantially higher than 90° C., and thereafter separating said solution from said triglyceride fat.

7. The method of making a stable triglyceride oil which comprises washing a normally liquid triglyceride oil with a solution of glycine and phosphoric acid in a fat-immiscible polar solvent selected from the class consisting of water, aqueous alcohol and glycerine, said washing being effected at a temperature not substantially lower than 50° C. and not substantially higher than 90° C., separating said solution from said triglyceride oil and thereafter adding an antioxidant for triglyceride oil to the resulting washed triglyceride oil.

8. The method of making a stable triglyceride fat which comprises washing a triglyceride fat having a melting point of less than 90° C., in liquid form, with a solution of glycine and phosphoric acid in a fat-immiscible polar solvent selected from the class consisting of water, aqueous alcohol and glycerine, said washing being effected at a temperature not substantially lower than 50° C. and not substantially higher than 90° C., separating said solution from said triglyceride fat and thereafter adding an antioxidant for triglyceride fat to the resulting washed triglyceride fat.

9. The method of making a stable vegetable oil which comprises washing a vegetable oil with a water solution of glycine and phosphoric acid at a temperature below 95° C., and separating said water solution from said vegetable oil following said washing.

10. The method of stabilizing lard against oxidation which comprises washing lard with a water solution of glycine and phosphoric acid at a temperature at which said lard is molten but below 95° C., and separating said solution from said lard following said washing.

11. The method of making a stable vegetable oil which comprises washing a vegetable oil with a water solution of glycine and phosphoric acid at a temperature not substantially lower than 50° C. and not substantially higher than 90° C., separating said water solution from said vegetable oil, and adding a fat-soluble antioxidant to the resulting washed vegetable oil.

12. The method of making a stable lard which comprises washing lard with a water solution of glycine and phosphoric acid at a temperature at which said lard is molten but not substantially lower than 50° C. and not substantially higher than 90° C., separating said water solution from said lard, and adding a fat-soluble antioxidant to the resulting washed lard.
